UNITED STATES PATENT OFFICE.

ELLIE MELTZER, OF NEW YORK, N. Y.

HAND BAG.

Application filed April 28, 1925. Serial No. 28,457.

To all whom it may concern:

Be it known that I, ELLIE MELTZER, a citizen of Russia, and a resident of the city of New York, borough of Manhattan, in the county and State of New York, have invented a new and Improved Hand Bag, of which the following is a full, clear, and exact description.

This invention relates to ladies' hand bags and has for an object to provide an improved construction wherein the parts are so formed that they may be adjusted to convert the bag from a leather bag to a cloth bag and the reverse.

Another object of the invention is to provide a hand bag formed of at least two different materials and provided with an arrangement of flaps and associated parts which may be adjusted to present to view either of two covering materials so that the bag will appear for instance, as a leather bag or a cloth covered bag.

In the accompanying drawing—

Figure 1 is a perspective view of a bag disclosing an embodiment of the invention, one of the flaps being shown partly unfolded.

Figure 2 is a view with both of the flaps turned over so as to occupy a position beneath the main body as shown in Figure 1.

Figure 3 is a sectional view through Figure 1, taken approximately on line 3—3, the covering flap being shown closed.

Figure 4 is a sectional view through the bag in its adjusted position, the same being taken on section 4—4 of Figure 2.

Referring to the accompanying drawing by numerals, 1 indicates what may be termed a pocketbook structure, the same being of any desired kind. This structure is provided with flanges or sections 2 and 3 extending to a position near the bottom of the main part of the pocketbook and at that point secured to side members 4 and 5 which form the outside members of the pocketbook 1 so as to complete the openings or pockets 6 and 7 while the main pocket 8 is closed by suitable fasteners 9. The side member 4, as shown in Figure 3, extends from the bottom of the pocket past the fasteners 9, across the top of the pocketbook where it presents a section 10 and down over the opposite side where it presents a flap 11. In forming the side 4, the same may be made from two different materials, as for instance, from a

strip of leather 12 and a strip 13 of cloth which is preferably silk though it could be of other material without departing from the spirit of the invention.

As shown in Figure 3, the side member 5 is bent back on itself at 14 whereby it presents a covering flap 15 held in place by a strap 16 stitched or otherwise secured at 17 to member 3 and also to the side 5. The free end of the strap 16 is provided with a socket 18 adapted to receive the stud 19, which stud is permanently connected with a covering flap 15. The covering flap 15 is also provided with a socket 20 adapted to receive a stud 21 permanently secured to the flap 11. The strap 16 on one surface consists of cloth, as for instance, silk, and on the other leather.

When the parts have been adjusted as shown in Figures 1 and 3, the bag appears to be a complete leather bag. When the two flaps 11 and 15 are turned from the position shown in Figures 1 and 3 to that shown in Figures 2 and 4, the leather members will be facing inwardly and the cloth portions outwardly so as to present what appears to be a silk bag. When the parts are turned to the position just described, the socket 22 will be positioned to receive the stud 19 while the stud 21 fits into the socket 18 of strap 16. It will, therefore, be noted that by merely reversing or turning over flaps 11 and 15 from the position shown in Figure 1 to that shown in Figure 2 will in effect, convert the bag from a leather hand bag to a cloth covered hand bag. When the flaps are moved in a reverse direction, a leather covered hand bag will be presented.

What I claim is:

1. A lady's hand bag, comprising a pocketbook structure and covering side members therefor, each side member being formed with a flap, and means for fastening both flaps on the same side of the pocketbook.

2. A lady's hand bag capable of being adjusted to present a leather or a cloth covered structure, said bag comprising a pocketbook structure, a pair of side members therefor, each of the side members being formed with a leather facing and a cloth facing, each of said side members being also formed with a flap, and means capable of engaging either of said flaps for holding the same against either of the sides of the pocketbook whereby when the flaps are adjusted to

overlap one side of the pocketbook the leather will be exposed to view and when the flaps are adjusted to fit against the opposite side of the pocketbook the cloth cover will be exposed to view.

3. A lady's hand bag, comprising a pocketbook, a pair of side members each formed with a flap substantially as long as the side members, and means including a strap for holding either of said flaps against the respective sides of said pocketbook.

4. A lady's hand bag, comprising a pocketbook structure provided with a pair of side members, each of said side members being formed from a piece of leather on one face and cloth on the opposite face, said side members being substantially twice the width of the pocketbook structure, said side members being foldable on themselves so as to act as a covering member, and means including a strap acting to hold one of said side members folded upon itself while allowing the other side member to act as a closure flap for the hand bag.

5. A lady's hand bag, comprising a pocketbook structure, a cover therefor formed twice as wide as the pocketbook structure and constructed of leather on one face and cloth on the opposite face, the extra width of said side members acting alternately as closure flaps and alternately as a covering structure, means including a strap for holding said flaps in position as covering struc-

tures, and means for holding said flaps closed when acting as closure flaps.

35

6. A lady's hand bag, comprising a pocketbook structure formed with a side member on each side of the pocketbook structure, each of said side members having a facing of leather and a facing of cloth, a portion of said side members projecting beyond the pocketbook acting at one time as a closure flap and at another as a covering member, snap fasteners for holding said closure members in a closed position, and a single strap connected with said pocketbook adapted to be folded in either of two directions for holding the covering members folded and against the respective sides of the pocketbook.

45

7. A lady's hand bag, comprising a pocketbook structure, a cover therefor, said cover including a pair of flaps as long as the pocketbook structure, each of said flaps being constructed of leather on one face and cloth on the opposite face, and means for securing said flaps in position so as to expose either face to view whereby when arranged in one position the cloth will be exposed to view and the bag will appear as a cloth bag and when arranged in another position the leather face will appear and the bag will present the appearance of a leather bag.
